INDICATING CONTROLLER FACE

Marion Pastoric, Chesterland, and Kenneth L. Vouk, Willowick, Ohio, assignors to Bailey Meter Company, a corporation of Delaware

Filed Jan. 5, 1966, Ser. No. 474

Term of patent 14 years

(Cl. D52—6)

FIG. 1

FIG. 2

FIG. 3

FIG. 1 is a front perspective view of an indicating controller face showing our new design.

FIG. 2 is a front elevational view of the instrument face.

FIG. 3 is a side elevational profile view of the instrument face.

The back of the instrument face is plain and unornamented.

The essential features of the design are shown in full lines. The fragmentary broken line showing of the housing is depicted for illustrative purposes only.

We claim:

The ornamental design for an indicating controller face, substantially as shown and described.
